UNITED STATES PATENT OFFICE.

WILLIAM H. C. TAYLOR, OF KANSAS CITY, MISSOURI.

SHAVING KIT.

Application filed April 2, 1925. Serial No. 20,291.

This invention relates to improvements in shaving kits.

The primary object of this invention is to provide a device of the above mentioned character, adapted to contain a brush, and suitable soap in one package, so that access may be had to one or the other more readily.

Another object of this invention is to provide a shaving kit, which is compact, 10 and of a convenient shape, adapted to be carried in one's pocket or in a traveling bag, thereby affording a water-tight package when closed, that is readily carried without detriment to surrounding articles.

15. A still further object of this invention is to provide a device of the above mentioned character, adapted to carry powdered or congealed soap in the same package with a brush or lathering device.

20 Other objects and advantages of the invention will be apparent during the course of the following description.

In the accompanying drawings forming a part of this specification and in which like 25 numerals are employed to designate like parts throughout the same,

Figure 1 is a side elevational view of the invention,

Figure 2 is a longitudinal sectional view 30 of the same showing the manner in which the device is assembled,

Figure 3 is a longitudinal sectional view of the brush projecting out of the receptacle,

35 Figure 4 is a side elevational view similar to Fig. 3, showing the brush in an inoperative position,

Figure 5 is a transverse sectional view of the brush socket and container, taken on 40 lines V—V of Fig. 1,

Figure 6 is a side elevational view of the preferred form of soap used in the shaving kit,

Figure 7 is a modification of the soap 45 container showing an arrangement for using powdered soap.

In the drawings, wherein for the purpose of illustration is shown a preferred embodiment of the invention, attention being 50 called to Figures 1 to 6 inclusive, the numeral 7 designates a brush housing which is cylindrical in shape being closed at one end and open at the other end.

Slidably mounted within the brush housing 7, is a brush socket 8, having bristles 9, mounted therein by means of a suitable ad-

hesive, such as sealing wax. The brush housing 7, is provided with a pair of oppositely disposed longitudinal slots 10, having oppositely disposed lateral slots 11, from 60 the main slots at the ends thereof, adapted to receive pins 12 formed on the opposite sides of the brush socket 8, to lock the brush in an operative or inoperative position. A coil spring 13, may be employed, coiled 65 within the brush housing 7, having one end resting on the bottom thereof, and the other end pressing against the brush socket 8, for projecting the brush 9, out of the housing 7, when it is desired to use the brush for lathering purposes. Near the opening of the brush housing 7, is formed an annular bead 14, adapted to limit the downward movement of a cylindrical receptacle 15, thereon. The cylindrical receptacle 15 is provided with a bottom 15^a, adapted to form a closure for the brush housing 7 when the two are fitted together, the top of the cylindrical receptacle being open to receive a shaving stick holder 16, and a stick of shav- 80 ing soap 17, the shaving stick holder 16 being provided with an annular flange 18, to limit the movement of the shaving stick 17 in the cylindrical receptacle 15.

In Fig. 7, is shown a modification of a 85 soap container, wherein the shaving stick holder 16, as shown in Figures 1, 2 and 6 could be lengthened to the length of the shaving stick 17, to form a container 16^a for powdered soap 17^a, the open end of the 90 lengthened soap container 16^a, being screw threaded to receive a closure 19, having perforations 20, to allow the powdered soap to be dispensed from the soap holder 16^a. A rotatable shutter 21, having openings 22, 95 adapted to align with the perforations 20, is attached to the closure 19 by means of a pin 23, allowing the rotatable shutter 21, to be rotated and cover or uncover the perforations 20.

For a consideration of the operation of the shaving kit the brush housing 7, is detached from the cylindrical receptacle 15, and the brush 9 is projected from the brush housing 7, by turning the pin 12 formed on the brush socket 8, in the bayonet slots 11, and then pushing the pins 12, longitudinally in the slots 10 to engage the bayonet slots at the open end of the brush housing 7, with the pins 12 seated in the recesses 11^a 110 at the closed ends of the slots 11, thereby keeping the brush in an operative position

while the same is used for lathering purposes. A supply of soap is contained in the cylindrical receptacle 15, and when withdrawn therefrom may be used to supply the brush with lather for shaving.

It is to be understood that the forms of my invention herewith shown and described are to be taken as preferred examples of the same, and that various changes in the shape, 10 size, and arrangement of parts may be resorted to without departing from the spirit of my invention, or the scope of the subjoined claim.

Having thus described my invention, I 15 claim:—

In a shaving kit a brush housing having longitudinal slots formed with lateral end extensions, a brush socket slidably mounted

in the housing and having projections adapted to be received in the longitudinal 20 slots, a coil spring having one end resting on the bottom of the brush housing and the other end pressing against the brush socket to hold the brush in a projected position, a cylindrical receptacle, being closed 25 at its lower end, adapted to fit on the open end of the brush housing forming a closure therefor, a shaving stick inserted in the open end of the cylindrical receptacle, and an annular struck-out portion formed at the 30 open end of the brush housing to limit the downward movement of the cylindrical receptacle thereon.

In testimony whereof I aff x my signature.

WILLIAM H. C. TAYLOR.
